UNITED STATES PATENT OFFICE

1,995,072

METHOD AND MEANS FOR REMOVING SEDIMENTATION FROM BOTTLED LIQUIDS

Perley B. Mills, Sabina, Ohio

Application September 19, 1932, Serial No. 633,837

1 Claim. (Cl. 210—55)

This invention relates to an improved method and apparatus for removing sedimentation from bottled beverages and has for an object to provide a simple yet effective method and device whereby fluid sedimentation or solid matter occurring in bottled liquids may be readily and substantially removed from such liquids immediately prior to the consumption thereof and removal of the liquids from their containers.

10 Certain types of fermented and unfermented beverages, as well as liquids used for non-beverage purposes, contain when bottled, finely divided particles of solid matter in suspension therein, which matter precipitates after the bottled liquids have been allowed to stand for some considerable time. These solids are often objectionable when the liquid is removed from the bottles for beverage or other purposes, and the present invention resides largely in the provision of a simple mechanical device which may be inserted in the bottles during the filling thereof with the liquid containing the objectionable solid matter and retained against displacement by the removable closures, caps or stoppers used in the sealing 25 of such bottles, whereby upon the subsequent removal of the closures, the said device may be actuated to mechanically withdraw the suspended solid matter from the liquid so that the latter will be left substantially free from such solid matter 30 for any desired use.

In the preferred form of the invention, I employ a sediment remover which comprises a soft, yieldable and pliable body, preferably formed from material such as sponge rubber, to which is connected a handle member extending upwardly and axially therefrom, the said yieldable body being so proportioned that normally it possesses a greater diameter than the neck of a bottle, but upon the actuation of the handle, the said body 40 may be compressed and withdrawn from the bottle through the open neck thereof, the withdrawal of the body serving to mechanically expel the undesired solid matter from the bottle and the liquid containing the same.

45 For a further understanding of the invention, reference is to be had to the following description and the accompanying drawing, wherein:

50 Fig. 1 is a perspective view of the improved sediment remover comprising the present invention;

55 Fig. 2 is a vertical sectional view taken through a bottle, disclosing the position of the remover in the bottle during storage of the liquid, wherein the bottle is shown in an inverted position per-

mitting of the accumulation of sedimentation in the neck thereof;

5 Fig. 3 is a similar view disclosing the bottle in its normal upright position and in an uncapped state, with the flexible body of the device compressed in the neck of the bottle and expelling sedimentation through the neck of the bottle;

Fig. 4 is a perspective view, partly in vertical section, of a modified form of the invention wherein the sediment remover is directly connected 10 with a bottle closure or stopper;

Fig. 5 is a view of a bottle stored right side up, showing the sediment collected at the upper end thereof;

Fig. 6 is a view showing a slightly modified 15 form of the invention in use.

Referring more particularly to the drawing, the numeral 1 designates the improved sediment remover device comprising the present invention in its entirety and in the form thereof disclosed in 20 Figs. 1 to 3, the said device preferably provides a body 2 composed of a soft yieldable material, such as sponge rubber. In this instance, the body is of disk-like form, although it may be of other forms and yet attain the ends of the invention, as 25 well as being made from materials of a flexible character other than sponge rubber. Connected with the body and extending upwardly therefrom is a handle 3 in the form of a suitable length of wire or rubber rod, which is anchored to the body 30 as indicated at 4. The upper end of the handle may be provided with a loop or the like 5 to facilitate its manipulation. Preferably, the body 2 possesses a diameter normally greater than that of the restricted neck 6 of a standard bottle 7, so 35 that when the body is drawn through the neck, it is to some degree compressed in order to closely engage with the inner walls of the neck to substantially prevent seepage of matter between the body and neck walls, and to serve in a piston-like 40 capacity in expelling the undesired matter.

In practice, the device is placed in the bottle 7 after the latter has been filled to a desired extent with a suitable liquid or beverage and the bottle is capped as at 8 in the ordinary manner. The 45 length of the handle rod 3 is such that when the bottle is capped, the said handle rod will be flexed or bowed, whereby when the bottle is subsequently uncapped, the said rod by reason of its resiliency will straighten so that the looped 50 end thereof will project above the neck of the bottle where it may be grasped to actuate the device. After the device has been inserted in a bottle filled with a given liquid containing solid matter in suspension therein, the bottle is capped 55

and is then inverted, as shown in Fig. 2, which during a period of storage or other inactivity, permits the solid matter to precipitate and collect in the neck of the bottle as indicated at 9. 5 Where the sediment is lighter than the liquid and during storage rises to the top of the liquid, the bottle is stored on its base, as shown in Fig. 5 of the drawing. When it is desired to withdraw the liquid from the bottle, the latter is placed upright and the cap or other closure 8 removed, 10 permitting the looped end 5 of the handle 3 to project beyond the open upper end of the bottle where it may be at once grasped. Since the solid matter is comparatively light in most instances, it does not immediately settle to the base 15 of the bottle but remains for an appreciable period suspended in the liquid in the neck of the bottle. Then, by drawing the device outwardly through the bottle neck, by the use of 20 the handle 3, the flexible rubber body 2 is compressed and crowded through the neck of the bottle, expelling the solid matter or sedimentation which collects above it, so that substantially 25 all of such sedimentation is removed, leaving the liquid in a clear bright state suitable for consumption as a beverage or for other purposes. Moreover, if the liquid contains carbon dioxide or 30 other effervescence creating gas, a portion of the gas accumulates above the surface of the liquid and since it is greatly desirable that some liquids 35 and beverages be highly charged with these gases at the time of consumption, it follows that in place of these gases escaping as takes place when the bottle is opened as in normal bottling, the act of placing the bottle in an upright position to properly actuate the device, causes the gas to rise 40 and diffuse through the liquid, thereby causing the liquid to absorb a substantial portion of these gases, thereby creating a more desirable highly carbonated liquid or beverage. Further, the 45 movement of the body 2 through the neck, or its momentary retention in the neck, serves to retain the effervescence producing gas contained in the bottle, preventing its violent and sudden release, so that the liquid when subsequently poured from the bottle will retain to a greater extent its desired effervescent qualities.

As shown in Fig. 4, it may be desirable to directly connect the device with the removable bottle cap or stopper. Such a stopper has been 50 indicated at 10, and consists of the usual rubber body formed to provide a plug which is tightly inserted into the normally open neck of the bottle, the plug being surrounded by an integral annular skirt 11, which may be flexed downwardly to 55

frictionally embrace the outer bead of a bottle neck to prevent communication between the interior of the bottle and the atmosphere. In this form of the invention, by the mere removal of the stopper, the sediment remover may be operated in conjunction therewith. In Fig. 4, the connection 12 between the body 2 and the stopper 10 may be of metal, rubber or other suitable material, and this is likewise true of the handle disclosed in the form of the invention set 10 forth in Fig. 1.

In Fig. 6, there is disclosed a slightly different form of the invention wherein the sediment receiving device 13 is made entirely of rubber and is formed so that it will float on top of the liquid. 15 Preferably, the elongated stem or handle 14 thereof is of a length greater than the diameter of the bottle so that the end of the handle will engage the side of the bottle and hold the device substantially vertical therein. It will be seen 20 that in turning the bottle right side up, the device will rise to the upper end thereof and the handle 14 will thus extend through the neck of the bottle where it may be readily grasped and the device removed from the bottle neck.

In view of the foregoing, it will be seen that by virtue of the construction described, as well as by following the method set forth, bottled liquids containing solid matter of an objectionable character may be freed from such matter prior to the 30 discharge of the liquid from the bottle. The device is essentially simple in character, may be produced at low costs and its materials are such that the liquid will not be deleteriously affected thereby.

What is claimed is:

A device for removing sedimentation from bottled liquids comprising a body of compressible material chemically inert to a bottled liquid, said body being adapted to be positioned within a 40 bottle in contact with the base of the bottle, the said body normally possessing a diameter greater than that of the neck of the bottle in which it is placed and capable of being compressed to pass through the bottle neck when drawn outwardly, and a flexible handle member for said body, said handle member being of a length in excess of that of the bottle and arranged to engage with a removable closure for the bottle whereby said handle member is flexed during storage of the bottle and upon the removal of the closure will straighten and protrude from the bottle in order to be conveniently grasped for withdrawal therefrom.
